BOTTLE HANDLING RACK

Lawrence W. Patterson, 1420 W. 5th St., Santa Ana, Calif.

Filed Sept. 8, 1961, Ser. No. 66,661

Term of patent 14 years

(Cl. D14—3)

The bottles and cartons shown in broken lines are included for illustrative purposes only.

I claim:

The ornamental design for a bottle handling rack, as shown and described.
